GESELLSCHAFT, OF WERNERWERK SIEMENSSTADT NEAR BERLIN, GERMANY

TELEPHONE SYSTEM

Application filed July 22, 1932, Serial No. 623,959, and in Germany August 19, 1931.

The present invention relates to a circuit arrangement for switches in telephone systems.

The object of the invention is to speed up the testing operation as far as possible in telephone systems employing rapidly operating switches and this is achieved by the provision of devices which cause the driving magnet of the switch to influence the test relay inductively.

In arrangements of this type it may occur that when the switch is set on a line to be seized the driving magnet releases the locking pawl too soon with the result that the switch wipers pass the line to be seized due to their momentum. This, according to the invention, is avoided by means of switching devices which retard the armature movement of the driving magnet when the switch is being set on a line to be seized.

An embodiment of the invention is shown in Figs. 1 and 2 in the drawing. The invention, however, is not limited thereto. Only the circuit details necessary for the understanding of the feature of the invention have been shown.

Whereas Fig. 1 shows a call finder circuit in which the arrangement according to the invention is utilized, Fig. 2 indicates another modification of the invention but only a test circuit and the auxiliary winding of the rotary magnet of a switch influencing the testing relay have been diagrammatically shown.

The subscriber of the subscriber's station T in Fig. 1 is able to set up connections in known manner over a call finder AS and switches succeeding this call finder. Only the preparatory stages of such a connection are shown as the arrangement according to the invention is mainly used in these stages. When the receiver is lifted in the subscriber's station T and consequently the switch hook is actuated, relay R is energized over the subscriber's line loop in the following circuit: earth, battery, resistance W1, contact 9t,

b-lead, of the subscriber's line, subscriber's station T, a-lead of the subscriber's line, contact 8t, winding of relay R, earth. Relay R actuates its contacts 1r and 2r and the closing of 1r marks the calling subscriber's line in the bank contact of the switch wiper c1 of the call finder AS. The following circuit for relay R1 is completed when contact 2r is closed: earth, battery, winding of relay R1, contact 15p in normal position, contact 2r, earth. Relay R1 is energized and closes its contacts 3r1 and 4r1. The closing of contact 3r1 completes the following circuit for winding I of the rotary magnet D of the call finder AS: earth, battery, contact 3r1, self interrupter contact 5d of the rotary magnet D, winding I of rotary magnet D, contact 6p, earth. The rotary magnet D is advanced in known manner in this circuit which is intermittently cut off by the contact 5d every time the magnet is energized. A winding II of the rotary magnet D is connected in series with windings I and II of the test relay P over contact 4r1. When the switch wipers a1—c1 of the call finder AS encounter the calling line, the following circuit is closed: earth, battery, windings of relay T, contact 1r, c1-wiper of the call finder AS, windings I and II of the test relay P, winding II of the rotary magnet D, contact 4r1, earth. When the rotary magnet has set its wipers to the calling line, an induced impulse is transmitted to winding II of the rotary magnet on the opening of contact 5d and this impulse accelerates the energization of the test relay P.

This relay which together with relay T operates in the above mentioned circuit opens its contact 6p and by cutting off the rotary magnet circuit brings said rotary magnet to rest. Contacts 10p and 11p switch through the line to the succeeding group selector. The closing of contact 16p causes relay R1 to relapse and the start line to be switched through to the succeeding call finder. Relay

T, by actuating its contacts 8t and 9t disconnects the winding of relay R from the calling line and after contact 1r has been opened closes its own locking circuit by means of its 5 contact 12t. The closing of contact 7p short circuits the high resistance winding II of the relay with the result that another call finder cannot be set to the incoming line.

In order to prevent the switch which operates with great speed from passing over the calling line contact due to its momentum after the release of the rotary magnet D and the therewith associated release of the locking pawl from the switch wheel, the release 10 of the rotary magnet is retarded when the switch wipers encounter a calling line (or an idle line). This is accomplished by winding II of the rotary magnet which, as previously mentioned, causes the test relay to be influenced inductively with the result that it is 15 rapidly energized, causing the rotary magnet also to operate with slow action due to the fact that said winding II of the rotary magnet is connected to battery in the test circuit. 20

25 When after the end of the conversation the calling subscriber replaces his receiver, contact 17m is opened which causes the circuit of relays P and T to be cut off with the result that all the relays then are restored to normal.

Fig. 2 of the drawing illustrates diagrammatically in which manner the auxiliary winding III of the test relay P1, the windings I and II of which are disposed in a test circuit extending over a wiper c2 of a switch, is inductively influenced on each step of the rotary magnet D1 with the aid of winding II of the rotary magnet, D1, that is to say in which manner it is pre-magnetized during 30 each step executed by the switch for example during the setting of said switch. Relay P1 is energized in known manner when wiper c2 encounters a line to be seized and to which battery has been applied.

45 The arrangement may also be so made that the test relay is energized by means of the induced current only. In such a case the C-lead of the seized lines has to be cut off and earth applied to the test circuit on both sides. 50 The test relay, when energized, would then have to close its own locking circuit.

What is claimed is:

1. In a telephone system, a rotary switch, a driving magnet for setting said switch, a 55 test relay, and means for causing said magnet to influence said test relay inductively during the setting movement.

2. A system as claimed in claim 1, in which the driving magnet of the switch is provided 60 with an auxiliary winding that is connected in series with the test relay.

3. A system as claimed in claim 1, in which the magnet is provided with an operating winding and an auxiliary winding that is inductively coupled with the operating winding 65

and included in a circuit with the test relay so that the induced current generated by the opening of the circuit including the operating winding will accelerate the operation of the test relay when the switch is set to a definite 70 position.

4. In a hunting switch, a rotary magnet, trunk lines accessible to said switch, means for operating said magnet to advance the wipers of said switch step-by-step to find one of said trunk lines, a test relay operated when said one trunk line is encountered to prevent further advancement of said wipers, and means associated with said rotary magnet for insuring the rapid operation of said test 75 relay when said trunk line is encountered.

5. In a hunting switch, a magnet for advancing the wipers of said switch step-by-step, a line, means for operating said magnet to advance said wipers to find said line, a test 80 relay for preventing further advancement of said wipers when said line is encountered, and means inductively related to said magnet for accelerating the operation of said test relay when said line is encountered by 85 the wipers of the switch.

6. In a hunting switch, a rotary magnet, a subscriber's line, a circuit including a primary winding on said magnet for advancing the wipers of said switch step-by-step to 90 find said line, a test relay operated when said line is encountered to prevent further advancement of said wipers, and an inductively related secondary winding on said magnet included in a circuit with said test relay in 95 which an induced current is generated when the wipers are advanced to said line to speed up the operation of said test relay.

7. In an automatic switch, a stepping magnet, a circuit including a first winding 100 of said magnet for operating the magnet, a test relay, and a circuit including a second winding of said magnet in which an induced current is generated when the circuit of the operating winding is opened for partially 105 operating said test relays.

8. In an automatic switch, a rotary magnet for advancing the wipers of the switch step-by-step, two inductively related windings for said magnet, means for closing a 110 circuit for one of said windings to operate said magnet to advance the wipers, a test relay having a plurality of windings, a circuit including the other winding of the magnet and one winding of said test relay for partially energizing said test relay each time the wipers of said switch are advanced a step, and a circuit including the remaining windings of said test relay completed when the wipers of said switch are advanced to a pre-determined position for fully operating the 115 partially energized test relay.

9. In an automatic telephone system, a calling subscriber's line, an automatic stepping switch, means responsive to the initia- 120

tion of a call by said subscriber for marking a contact in the bank of said switch and for initiating the automatic stepping movement of the switch, a test relay partially energized by induced current generated each time said switch is stepped, a circuit for energizing the test relay all the way when the marked contact is encountered, and means responsive to the complete energization of said test relay for preventing further automatic stepping of the switch.

In witness whereof, I hereunto subscribe my name this 24th day of June, 1932.

RUDOLF WOLF.
